TRACTION DEVICE

James W. Boughton, Chicago, Ill., assignor to Electric Parts Corporation, Chicago, Ill., a corporation of Illinois

Application December 7, 1953; Serial No. 396,586

4 Claims. (Cl. 203—200)

This invention relates to traction devices adapted for use in moving elongated flexible material, such as wire, tubing, hose, tape, strips, etc., and has for an object the provision of a traction device in which the flexible material is frictionally engaged within the groove of a sheave by means of a pair of endless belts.

For example, the traction device is adapted for use in the manufacture of coated wire or tape and the extrusion of tubing, hose or strip stock. It may also serve as a drive for various types of machines, or for moving a wire or tape through a magnetic recording machine.

Briefly, the present invention comprises two endless belts extending around a plurality of sheaves, the belts converging into the annular groove of one sheave to frictionally engage therein the wire, or other material to be moved, and the belts diverging from the groove of said one sheave at a point circumferentially spaced from their point of convergence to free the wire for movement away from the sheave.

Traction devices heretofore employed for moving wire and the like usually comprised a pair of coating nip rolls which merely engage points at opposite sides of the wire. The present invention contemplates the provision of a traction device in which line contact frictional engagement is provided along three sides of the material being moved to insure adequate traction without damage to the material.

This invention further contemplates the provision of a traction device in which the several parts thereof are formed and arranged to facilitate threading of a length of flexible material thereto for movement therethrough.

Another object of the invention resides in the provision of a traction device which is relatively simple and inexpensive in construction and reliable in operation.

This invention embodies other novel features, details of construction and arrangement of parts which are hereinafter set forth in the specification and claims and illustrated in the accompanying drawings, wherein:

Fig. 1 is a top plan view illustrating a traction device embodying features of the invention.

Fig. 2 is a longitudinal sectional view taken along the line 2—2 of Fig. 1.

Fig. 3 is an enlarged detail sectional view taken along the line 3—3 of Fig. 2.

Fig. 4 is a detail sectional view, corresponding to Fig. 3, illustrating a modified form of the invention.

Fig. 5 is a detail sectional view, corresponding to Fig. 3, illustrating another modified form of the invention.

Referring now to the drawing for a better understanding of the invention and more particularly to Figs. 1 to 3 therein, the traction device is shown as comprising shafts 6, 7 and 8 journaled for rotational and non-axial movement in suitable bearings provided in side frames 9—9, the shaft 6 being connected to an electric motor or other source of power (not shown).

A driving sheave 11 is keyed to the shaft 6, a pair of axially spaced driven sheaves 12 and 13 are keyed on

2

the driven shaft 7, and a pair of axially spaced tension adjustment sheaves 14 and 16 are keyed on the shaft 8. A pair of endless belts 17 and 18 are mounted on the sheaves 12—14 and 13—16, respectively, and converge therefrom into the annular groove 19 of the driving sheave 11. As illustrated in the drawing, the upper flights of the belts 17 and 18 converge from their respective driven sheaves 12 and 13 toward the driving sheave 11, and the lower flights of the belts diverge from the driving sheave toward their respective tension adjustment sheaves 14 and 16.

As viewed in transverse section in Fig. 2, the annular groove 19 of the driving sheave 11 is defined by opposed, axially spaced annular side surfaces 21—21 converging inwardly toward and merging with a circular inner surface 22, and the endless belts 17 and 18 are of circular cross section for engagement between the side surfaces 21—21 and biased toward the inner surface 22, by the tension adjustment sheaves 14 and 16 to cause wire W, or the like, to be engaged between the belts and against the inner surface 22 throughout a portion of the circumference of the latter.

To vary the clamping force exerted by the belts 17 and 18 against the wire W, shaft 8 is journaled in bearings 23—23 adjustably mounted in slots 24—24 formed in the side frames 9—9, the bearings being adjustably positioned within their respective slots by means of adjustment screws 26—26 threaded through bosses 27—27 on the side frames to increase or decrease the tension applied to the endless belts.

In the operation of the traction device thus shown and described, the wire W is frictionally engaged between the surface 22 of the driving sheave and the endless belts throughout a portion of the circumference of said surface and is progressively fed through the device for discharge to any desired place, such as a hopper. It will also be noted that the clamping force exerted by the endless belts against the wire may readily be varied by means of the adjustment screws 26—26.

Fig. 4 illustrates a modified form of the invention in which the traction device is provided with a pair of conventional endless belts 31—31 of the type commonly referred to as V-belts, the belts being formed and arranged to engage a wire W against the inner surface 22 of a groove 19 formed in a driving sheave 11. This form of the invention is otherwise similar to the form heretofore shown and described.

Fig. 5 illustrates another modified form of the invention in which the traction device is provided with a pair of endless belts 32—32 of triangular section mounted within the grooved driving sheave 11 to engage a wire W. This form of the invention is otherwise similar to the form heretofore described in connection with Figs. 1 to 3 in the drawing.

While this invention has been shown in several forms, it is obvious to those skilled in the art that it is not so limited, but is susceptible of various changes and modifications without departing from the spirit and scope of the claimed invention.

I claim:

1. In a traction device for moving a flexible element, a rotatable traction sheave having an annular groove defined by inwardly converging side surfaces and a circular inner surface, two endless driving belts engaged side by side between the side surfaces of said groove to clamp the flexible element against a segment of the circumference of said inner surface, said belts diverging from opposite sides of said sheave in planes substantially tangent to said sheave.

2. In a traction device for moving a flexible element, a rotatable traction sheave having an annular groove

defined by inwardly converging side surfaces and a circular inner surface, two endless driving belts engaged side by side between the side surfaces of said groove to clamp the flexible element against a segment of the circumference of said inner surface, a pair of driven sheaves engaged by related belts, said driven sheaves being axially spaced from said traction sheave and laterally spaced from each other, a pair of axially spaced belt tensioning sheaves engaged by related belts, said belts converging from their respective driven sheaves for side by side 10 abutting engaging within said traction sheave.

3. In a traction device for moving a flexible element, a rotatable traction sheave having an annular groove defined by inwardly converging side surfaces and a circular inner surface, two endless driving belts engaged side by side between the side surfaces of said groove to clamp the flexible element against a segment of the circumference of said inner surface, a pair of driven sheaves engaged by related belts, said driven sheaves being axially spaced from said traction sheave and laterally spaced from each other one on each side of the traction sheave, a pair of belt tensioning sheaves engaged by related belts, said belt tensioning sheaves being axially spaced from said traction sheave and laterally spaced from each other one on each side of said traction sheave, said belts converging from their respective driven sheaves for side by side abutting engaging within said traction sheave, said belts diverging from said traction sheave toward their respective tensioning sheaves, and means to adjust the position of said tensioning sheaves relative to said traction and driven sheaves to vary the clamping force exerted by said belts against said element.

4. In a traction device for moving a flexible element, a rotatable traction sheave having an annular groove defined by inwardly converging side surfaces and a circular inner surface, two endless driving belts engaged side by side between the side surfaces of said groove to clamp the flexible element against a segment of the circumference of said inner surface, a pair of driven sheaves engaged by related belts, said driven sheaves being axially spaced from said traction sheave and laterally spaced from each other one on each side of the traction sheave, a pair of belt tensioning sheaves engaged by related belts, said belt tensioning sheaves being axially spaced from said traction sheave and laterally spaced from each other one on each side of said traction sheave, said belts converging from their respective driven sheaves for side by side abutting engaging within said traction sheave, said belts diverging from said traction sheave toward their respective tensioning sheaves, and means to adjust the position of said tensioning sheaves relative to said traction and driven sheaves to vary the clamping force exerted by said belts against said element.
